UNITED STATES PATENT OFFICE.

BURNHAM C. STICKNEY, OF ELIZABETH, NEW JERSEY, ASSIGNOR TO UNDERWOOD
TYPEWRITER COMPANY, OF NEW YORK, N. Y., A CORPORATION OF DELAWARE.

TYPEWRITING MACHINE.

Application filed April 13, 1921. Serial No. 460,954.

To all whom it may concern:

Be it known that I, BURNHAM C. STICKNEY, a citizen of the United States, residing in Elizabeth, in the county of Union and State of New Jersey, have invented certain new and useful Improvements in Typewriting Machines, of which the following is a specification.

This invention relates to combined means for connecting a typewriter to a base or support and preventing transmission of sound vibrations from the machine to the base. The invention is shown as applied to an Underwood standard typewriter.

One feature of this invention is the provision of simple and efficient mechanism whereby a typewriter may be supported and held firmly in position on a base or support, but which permits the machine to be readily removed from its base without detaching or operating any mechanism. Hitherto it has been customary to provide typewriters with rubber or felt feet which were screwed to the frame, and clamps were then provided to hold the machine on its base or support. The clamps had to be unscrewed or otherwise operated when it was desired to release the machine. The present invention provides a combined supporting and fastening or clamping means, which requires no operation of parts when it is desired to remove the machine from its base.

Another feature of this invention is the incorporation of sound-deadening material in the fastening means, so that a minimum amount of vibration is transmitted to the base which ordinarily acts as a resonator to amplify these vibrations and increase the noise of operation.

Still another feature of this invention is the ease with which the fastening means may be applied to an ordinary typewriter and the simplicity of assembling and disassembling the parts.

Other features and advantages will hereinafter appear.

In the accompanying drawings,

Figure 1 is a front view of an Underwood standard typewriter fixed to a base by the improved connecting means.

Figure 2 is a plan view, partly sectioned, of the device in Figure 1, the machine being broken away near the base.

Figure 3 is an end view, partly sectioned, of the device shown in Figure 1.

The illustrated typewriter comprises a main frame 10 in which is supported most of the operating mechanism, said frame having a forward extension 11 in which banks of keys 12 are positioned; the frame being usually mounted on a base or support 15. The frame is supported at each side thereof by a set of the improved connecting devices, each of said sets of devices comprising two co-operating members 16 and 17. The member 16 of each set is fixed to the frame of the machine by screws 18 passing therethrough and up into said frame, and is supported upon the cooperating member 17 fastened to the base or support by screws 19. Each member 16 comprises a flat, horizontally disposed, metal strip or plate 20 fixed to a side of the frame 10 by the screws 18, said member terminating in an outer portion 21 rolled or curved in the form of a tube to impart rigidity to the plate. Each member 17 similarly comprises a flat, generally horizontal, metal strip or plate 22 terminating in a rolled portion 23 in the form of a tube, concentric with tube 21, each flat strip 22 having forward and rearward extensions 24 through which pass screws 19 to hold member 17 to the base. It will be apparent that by properly positioning members 17 on the base, the machine can be slid rearwardly, so that members 16 telescope into members 17, the unclosed portion 25 of rolled portion 23 permitting strip 20 of member 16 to slide therein.

To facilitate inserting the inner tubes both tubes may be slightly tapered. The tapering telescopic arrangement of members 16 and 17 renders the insertion of members 16 into members 17 extremely easy, since the narrow rearward end of the former is inserted in the wide forward end of the latter. The end of each tube 23 is closed by a plate 29, which may be integral with member 17, and which limits the rearward movement of the tubes 21, and hence of the machine. When the tubes have been telescoped as described, the frame is held against side-wise movement, and the plates 29 prevent rearward movement. Since there is little or no forward movement of the machine, the latter is held firmly in position during operation thereof.

Since members 16 and 17 are preferably of metal, the contact of metal with metal would readily transmit the vibrations which

arise during typing to the base which acts as a resonator to amplify the sound. Members 16 and 17 are therefore kept out of contact at all points by a felt filler-member 30 in the shape of a tube fitting snugly on the interior of each tube 23. The diameter of the tube 21, which fits into tube 30, is therefore smaller than the diameter of tube 23 at any point along its length by twice the thickness of the felt composing member 30. The rear end of tube 21 is kept out of contact with plate 29 by a felt pad 31 fixed to said plate. By the above-described arrangement of parts, the vibrations of the machine transmitted by members 16 are absorbed by the felt members 30 and 31 before they can reach members 17 and hence the base. There is a decided reduction in the sound of operation due to this absorption of vibration by eliminating the metal-to-metal connection.

From the above description, it will be apparent that the typewriter, through members 16, is supported upon members 17, the members 16 being completely insulated from members 17 by a layer of sound-deadening material, such as felt, and that the co-operating, telescoping, tubular portions of members 16 and 17 together with end plates 29 provide a clamping means to hold the machine firmly in position during the typing operation. The machine need only be drawn forward to withdraw tubes 21 from tubes 30 and 23 in order to release the machine from its base 15.

It will be understood from the foregoing that each of the sets of connecting devices at the opposite sides of the frame 10 of the machine comprises a horizontal plate 20 secured to the frame 10, a second horizontal plate 22 lying upon and secured to the base 15, and a bed of insulating material in the form of the felt member 30, interposed between the plates 20 and 22. This construction is very effective in preventing transmission of vibrations from the machine-frame 10 to the base 15. In order to lock the frame 10 of the machine against vertical movement, the outer portion of the horizontal plate 22 is extended upwardly and inwardly about the outer portion of the plate 20, so as to cause the outer portions of the plates 20 and 22 to be arranged in intergripping relation with each other. To the end that the plate 20 may be made rigid, its outer portion is preferably curved upwardly and inwardly as indicated at 21, and in such an event the outer portion 23 of the plate 22 is also preferably curved upwardly and inwardly concentrically with the portion 21 of the plate 20. The outer portion of the bed of insulating material 30 is also extended upwardly and inwardly between the outer portions of the plates 20 and 22 so as not only to completely insulate the plates 20 and 22 from each other, but also to prevent

displacement of the horizontal portion of the felt member 30 relatively to the plates 20 and 22.

In order to cause the frame 10 of the machine to be locked against lateral movement, the plates 20 and 22 of the set of connecting devices at one side of the machine are arranged reversely to the plates 20 and 22 at the opposite side of the machine; that is, as viewed in Figure 1 of the drawings, the outer portions of the plates 20 and 22 at one side of the machine are curved inwardly toward the right, whereas such members at the opposite side of the machine are curved inwardly toward the left. With this construction, the outer portion 23 of the plate 22 at one side of the machine prevents lateral movement of the machine in one direction, and the outer portion 23 of the plate 22 at the opposite side of the machine prevents lateral movement of the machine in the opposite direction, so that the devices on both sides of the machine co-act to positively lock the machine against lateral movement of any kind. As hereinbefore indicated, the sets of connecting devices are preferably constructed so as to enable the machine to be connected to and disconnected from the base by a simple sliding movement, and, to facilitate the connection of the machine to the base in such a manner, the tubular portions 21 and 23 of the plates 20 and 22, respectively, are tapered from end to end toward the rear of the machine.

By reference to Figures 2 and 3, it will be noted that the plates 20 and 22 and the bed of insulating material 30 are all extended from the front of the frame 10 to the back of the frame. The plates 20 and 22 are consequently of such length as to enable them to support the machine without any substantial flexing movement so that a rigid support for the machine is provided. This construction also provides a large area of surface contact between each of the plates 20 and the corresponding felt member 30, so that when the machine has been moved rearwardly to slide the tubular portions 21 of the plates 20 into the housings provided by the felt members 30 and the tubular portions 23 of the plates 22, the machine will be held so firmly by friction between the parts of the connecting devices as to prevent it from being accidentally moved forward.

Variations may be resorted to within the scope of the invention, and portions of the improvements may be used without others.

Having thus described my invention, I claim:

1. In combination, a typewriting machine base and a typewriting machine located thereon with sound deadening means between the base and machine, said sound deadening means comprising a horizontally

- arranged plate having an enveloping portion extending parallel with the surface of the base and fastened on top of the same, insulating material on top of the horizontal part of the plate and around the interior of the enveloping portion and a member slideable within the interior of the insulating material and attached to the typewriter whereby without distorting said members or insulating material, the typewriter may be slid into and out of engagement with the base but held from either lateral movement rectangular to said sliding movement or vertical movement relative to the base.
2. In combination a base member, a typewriting member, one member having a horizontal plate attached thereto, said plate being turned over at one side, the other member having a second horizontal plate attached thereto, said second plate being also turned over at one side, an insulating piece on top of the first mentioned horizontal plate and within the first mentioned turned over portion and surrounding the second mentioned turned over portion, the construction being such that the typewriter is detachable from the base without distortion of the sound deadening portion by a sliding movement of the typewriter member parallel to the upper surface of the base, the enveloping turned over portion preventing vertical movement of the typewriter relative to the base or movements rectangular to said sliding movement.
3. In combination, a typewriter member and a base member, one of said members having attached to it on either side of the typewriting member, a horizontal plate turned over at its outer portion, the other member having a horizontal plate attached one on either side of the typewriting member and extending into the turned over portions of said other plates, insulating material extending under the bottom of the typewriter member and over the top of each of the horizontal plates and around in between the turned over portions and above and below the inwardly extended plates whereby the typewriter may be slid out of connection with the base member without distorting the sound deadening material but holding the typewriter from movement rectangular to said sliding movement or vertically independent of the base.
4. In combination with a typewriting machine, means for supporting the machine on a base and for preventing transmission of vibrations from the machine to the base such as would cause the base to act as a resonator to augment the sound produced by the machine, said supporting means comprising two horizontally-disposed plates secured to the machine and to the base, respectively, and a bed of sound-deadening material interposed between said plates, one of said plates being turned laterally and inwardly about the outer portion of the other plate so as to positively lock the machine and the plate carried thereby against movement relatively to the other plate and the base, and said bed of sound-deadening material being also extended laterally and inwardly between said plates, so as to completely insulate the plates from each other.
5. In combination with a typewriting machine, means for supporting the machine on a base and for preventing transmission of vibrations from the machine to the base such as would cause the base to act as a resonator to augment the sound produced by the machine, said supporting means comprising reversely-arranged sets of devices located on opposite sides of the machine, each of said sets of devices including a plate extending outwardly from one side of the machine, a second plate secured to the base, and a bed of sound-deadening material interposed between said plates, said first-mentioned plate being curved upwardly and inwardly at its outer portion to cause it to be rigid, said second-mentioned plate being turned upwardly and inwardly about the outer portion of the first-mentioned plate substantially concentrically with said outer portion so as to positively lock the first-mentioned plate and the machine against movement relatively to the second-mentioned plate and the base, and said bed of sound-deadening material being also extended upwardly and inwardly between said plates so as to completely insulate the plates from each other.
6. In combination with a typewriting machine, means for supporting the machine on a base and for preventing transmission of vibrations from the machine to the base such as would cause the base to act as a resonator to augment the sound produced by the machine, said supporting means comprising reversely-arranged sets of devices located on opposite sides of the machine, each of said sets of devices including an inner plate projecting outwardly from one side of the machine and extending substantially from front to back of the machine, an outer plate secured to the base and of a length substantially equal to that of the inner plate, and a bed of sound-deadening material interposed between said plates and completely insulating them from each other, said inner plate being curved upwardly and inwardly at its outer edge to cause it to be rigid, said outer plate being turned upwardly and inwardly about the outer portion of the inner plate substantially concentrically with said outer portion so as to positively lock the inner plate and the machine against movement relatively to the outer plate and the base, and said curved portions of said plates being tapered from end to end to enable each of the inner plates to be readily

engaged with said bed and the outer plate by slidable movement of the machine and the inner plates relatively to the outer plates and the base.

- 5 7. In combination with a typewriting machine, means for positively locking the machine to a base and for preventing transmission of vibrations from the machine to the base such as would cause the base to act 10 as a resonator to augment the sound produced by the machine, said locking means comprising a bed of insulating material and co-operating intergripping members extending substantially from front to back of the 15 machine and held out of contact with each other by the insulating material, one of said members being fixed to the machine and the other being fixed to said base, said first member being slidable into said second member 20 for positive locking engagement therewith, said machine being movable rearwardly to slide said first member into engagement with said second member for supporting and fastening said machine on said base, and 25 said machine being movable forwardly to disengage said members and release said machine from said base.

8. In combination with a typewriting machine, means for positively locking the machine to a base against vertical, rearward and lateral movement and for preventing transmission of vibrations from the machine to the base such as would cause the base to act 30 as a resonator to augment the sound produced by the machine, said locking means comprising a tubular bed of insulating material and inner and outer, rigid, tubular members, one of which is secured to the machine and the other to the base, said tubular bed of insulating material being contained within said outer tubular member and said inner member being slidable into said tubular bed and said outer member out of contact with the outer member but inter- 35 gripping with it, said machine being movable rearwardly to slide said inner member into locking relation with said outer member for supporting the machine and fastening it on said base, and said machine being movable forwardly to disengage said members and release said machine from said base.

9. In combination with a typewriting machine, means for positively locking the machine to a base and for preventing transmission of vibrations from the machine to the base such as would cause the base to act as a resonator to augment the sound produced by the machine, said locking means 55 comprising a tubular bed of insulating material and inner and outer, rigid, tubular members of different sizes, one of said members being fixed to the machine and the other to said base, said members being held 60 out of contact with each other by the in-

sulating material but intergripping so as to retain the insulating material against displacement relatively to the members and to positively lock the machine against movement relatively to the base.

10. In combination with a typewriting machine, means for positively locking the machine to a base against vertical, rearward and lateral movement and for preventing transmission of vibrations from the machine 75 to the base such as would cause the base to act as a resonator to augment the sound produced by the machine, said locking means comprising a tubular bed of insulating material and co-operating, substantially concentric, tubular members of different sizes held out of contact with each other by the insulating material, the smaller of said members being fixed to said machine and the larger of said members being fixed to 80 said base, said smaller member being slid- 85 able into said bed of insulating material and the larger member for locking engagement therewith, said machine being movable rearwardly to slide said smaller mem- 90 ber into said larger member for supporting the machine and fastening it on said base, and said machine being movable forwardly to disengage said members and release said 95 machine from said base, and means on said larger member for limiting the rearward movement of said smaller member therein.

11. In combination with a typewriting machine, means for positively locking the machine to a base against vertical, rearward and lateral movement and for preventing transmission of vibrations from the machine to the base such as would cause the base to act as a resonator to augment the sound produced by the machine, said locking means comprising reversely-arranged sets of devices located on opposite sides of the machine, each set of devices including a bed of insulating material extending substantially from front to back of the machine 100 and co-operating members having substantially concentric tubular portions, said bed of insulating material also having a tubular portion and said members being held out of contact with each other by the in- 105 sulating material and being of substantially the same length as the bed of insulating material, the smaller of said members with respect to its tubular portion being fixed to said machine and the larger of said members being fixed to said base, said smaller member being slidable within said larger member into locking relation therewith, said machine being movable rearwardly to slide said smaller member into said larger member for 110 supporting the machine and fastening it on said base, and said machine being movable forwardly to disengage said members and release said machine from said base.

12. In combination with a typewriting 115

machine, means for positively locking the machine to a base and for preventing transmission of vibrations from the machine to the base such as would cause the base to 5 act as a resonator to augment the sound produced by the machine, said locking means comprising co-operating, substantially concentric, tubular members of different sizes, the smaller of said members being fixed to 10 said machine and the larger of said members being fixed to said base, said smaller member being slidable within said larger member into locking relation therewith, said machine being movable rearwardly to 15 slide said smaller member into said larger member for supporting the machine and fastening it on said base, and said machine being movable forwardly to disengage said members and release said machine from said 20 base, means on said larger member for closing the bore of said member at its rear end to limit the rearward movement of said smaller member therein, and sound-deadening material interposed between said members and between said smaller member and the closing means on the larger member for 25 completely insulating said members from each other.

13. In combination with a typewriting 30 machine, means for positively locking the machine to a base against vertical, rearward and lateral movement and for preventing transmission of vibrations from the machine to the base such as would cause the 35 base to act as a resonator to augment the sound produced by the machine, said locking means comprising sets of devices located on opposite sides of the machine, each including a bed of insulating material and 40 co-operating members having tubular portions of different sizes, one of said members being fixed to said machine and the other of said members being fixed to said base, said members being adapted for relative

sliding movement, said machine being movable rearwardly to cause the smaller tubular portion of one of said members to enter the larger tubular portion of the other member for supporting the machine and fastening it on said base, the devices of the 45 set on one side of the machine being reversely arranged with reference to the devices on the other side of the machine so that the members on one side of the machine prevent lateral movement of the machine in one direction and the devices on the other side of the machine prevent lateral movement of the machine in the opposite direction, and said bed of insulating material having a tubular portion interposed 50 between the tubular portions of said first two members and completely insulating said first two members from each other.

14. In a typewriting machine, a frame and two horizontal tubular supporting and 55 securing members connected to the base of the frame at its opposite sides, said members projecting laterally from the frame and extending from the front to the rear thereof, and being adapted to be telescoped with 60 in co-operating tubular clamps on a supporting base for securing the machine to the supporting base, the supporting area of 65 said members being so great that the members and clamps will act as pressure-distributors to enable the machine to be supported upon soft, yieldable sound-deadening material interposed between the members and the clamps without compacting said material substantially, whereby the transmission 70 of vibration from the machine to the base, such as would cause the base to act as a resonator to augment the sound produced by the machine, is prevented.
